United States Patent Office

Des. 209,029
Patented Oct. 24, 1967

209,029

TELEPHONE INDEX OR THE LIKE

Richard McFadyen, Essex Fells, and William Macowski,
Montclair, N.J., assignors to Ketcham & McDougall,
Inc., Roseland, N.J., a corporation of New Jersey

Filed Mar. 17, 1966, Ser. No. 1,513

Term of patent 14 years

(Cl. D74—1)

FIG. 1

FIG. 2

FIG. 3

FIG. 4

FIG. 5

FIG. 6

FIG. 1 is a perspective view of a telephone index or the like showing our new design;

FIG. 2 is a top plan view thereof;

FIG. 3 is a front elevational view;

FIG. 4 is a right side elevational view;

FIG. 5 is a rear elevational view; and

FIG. 6 is a bottom plan view thereof.

We claim:

The ornamental design for a telephone index or the like, substantially as shown.
